CONSERVATION VENTING DEVICE AND
FLAME ARRESTERRudolph J. Anschicks, Chicago, Ill., assignor to
Protectoseal Company of America, Chicago,
Ill., a corporation of Illinois

Application January 31, 1936, Serial No. 61,719

5 Claims. (Cl. 220—88)

My invention relates to venting devices and more particularly it relates to closure devices for the vent openings of storage tanks containing oil, gas or other volatile substances, such devices being automatically operable to open both to permit the escape of vapors when the interior pressure exceeds a selected amount and to permit the ingress of air when the interior pressure falls below atmospheric pressure, the device otherwise remaining closed, thereby conserving the vapor by minimizing the flow from the tank.

Under occasional atmospheric conditions there is a tendency for the escaping vapors to saturate the atmosphere surrounding the tank to the point of inflammability and in the event of ignition when the vent is open, flame arresters must be provided if the resulting combustion is to be prevented from traveling either slowly or explosively into the tank. Ignition of the escaping vapors having occurred, it frequently happens that they burn continuously on the emergent face of the flame arrester so long as the venting device is open to permit their escape from the tank. Under some conditions, the combustion adjacent the arrester produces a blue flame of high temperature tending to heat the arrester either to the point of melting or to a temperature sufficient to ignite the inside vapors.

It is an object of the invention to provide an improved venting device including flame arresters adapted to permit prolonged burning of vapors on the emergent face of the arrester and to so control the condition zone that it is prevented from reaching the vent opening in the tank.

Another object of the invention is the provision of an improved fire baffle or flame arrester device adapted to permit gases to flow therethrough and their combustion on the emergent face to occur without heating the device to the melting point or its inner faces to a temperature sufficient to ignite the vapors.

A further object of the invention is the provision of an improved vapor conservation venting device of the kind described which is simple, easily assembled, inexpensive to manufacture, durable and satisfactory for its intended purpose.

Many other objects and advantages of the construction herein shown and described will be obvious to those skilled in the art from the disclosure herein given.

To this end my invention consists in the novel construction, arrangement and combination of

parts herein shown and described and more particularly pointed out in the claims.

In the drawings, wherein like reference characters indicate like or corresponding parts:

Fig. 1 is an elevational view partly in section of a flame-proof venting device embodying the principle of the invention;

Fig. 2 is a view along line 2—2 of Fig. 1;

Fig. 3 is an end elevational view of the device with a portion of certain members shown as partially removed;

Fig. 4 is a view along the line 4—4 of Fig. 3;

Fig. 5 is a view of one of a plurality of plates assembled to form a flame arrester; and

Fig. 6 is a sectional view of a flame arrester forming a portion of the device and illustrating a screen forming an auxiliary baffle or flame arrester.

Referring now more particularly to the drawings, the device is shown as including a valve housing 10 providing a chamber 11 open at one end. The open end of the housing is preferably circular and interiorly threaded to provide a fluid tight connection with a pipe 12. The pipe 12 is shown in vertical position and is adapted to provide a vent opening for an oil or gas storage tank, not shown, and through which inflammable vapors escape from the tank into the surrounding atmosphere.

The intermittent emission of vapors and influx of air through the vent opening due to varying tank pressure is in common parlance known as "breathing". The vapors so emitted by a breathing tank, are sufficient to entail a substantial loss if their escape is unretarded, and in order that the vapor loss be minimized, the chamber 11 is closed to the atmosphere by valve mechanism adapted to open when the pressure in the tank exceeds atmospheric pressure by an amount which the tank structure can safely resist. A conduit 13, extending through the chamber 11 and projecting laterally from opposite sides thereof, provides ports 14 and 15, respectively controlled by valves 16 and 17 for the escape of vapors and the admission of air to the tank. The weight of the valve 16 normally maintains it in the closed position of the port 14 until it is lifted by the pressure of the accumulated vapors in the tank and permits their escape whereby the internal tank pressure is lowered sufficiently that the valve is closed by gravity. The described operation of the valve 16 conserves the vapors since the port 14 thereby remains closed for all tank pressures except those exceeding the maximum determined by the weight of the valve. The

- valve 17 similarly maintains the port 15 closed for all tank pressures above a selected minimum less than atmospheric pressure. If the tank pressure falls below such selected minimum, the 5 valve 17 will be lifted from its seat and permit air to flow through the chamber 11 and into the tank, thereby relieving the vacuum conditions that might otherwise cause the tank to collapse under atmospheric pressure.
- 10 The vapors escaping from the tank through the conduit 13 will, under certain atmospheric conditions, collect in the vicinity of the tank and saturate the atmosphere sufficiently to render it combustible and explosive. The venting device 15 provides flame arresters mounted in the open ends of the conduit 13 adapted to prevent either explosive or slow travel of ignited gases from the exterior into the interior of the venting device. The flame arresters each consist of a grid comprising a plurality of vertically extending plates 18, arranged side by side and in spaced relation, the spacing between the assembled plates corresponding to the amount that projections 19, shown in Fig. 5, protrude from the plates.
- 20 The plates 18 are held in assembled grid forming relation by an inner annular member 20, an outer annular member 21, and an intermediate annular member 22, fastened together by bolts 23 to form a frame for the plates. The grid frames are fastened to the open ends of the conduit 13 by extending the bolts 23 through outwardly projecting flanges 24 provided on the conduits and clamping the frames to a fluid-tight fit with the flanges by means of cap nuts 25.
- 30 The members 20 and 21 respectively overlap and slidably fit the longitudinal edges of the plates 18 and the intermediate frame member 22 similarly fits the ends of the plates and the side of one marginal plate of each grid.
- 35 The plates 18 are held in contact with the projections 19 of the next adjacent plate by a bolt 26 mounted in one vertical wall of the member 22 in operative engagement with a pressure plate 27. The bolt 26 is operable to press the plates 18 together and thereby to maintain open spaces or apertures 29 between the plates corresponding in thickness to the amount the projections 19 protrude from the plates. A leaf spring 28, positioned between the member 22 and the plate 27, is also adapted to maintain the plates 18 in uniform closely spaced relation should the bolt 26 be accidentally loosened.
- 40 The bounding walls of the projecting ends of the conduit 13 are divergent outwardly preferably in an amount such that the total cross-sectional area of the exposed portions of the spaces 29 between the plates 18 is equivalent to the cross-sectional area of the most constricted portion of the conduit, so that the flow of gases outwardly or the flow of air inwardly is not retarded by the grid. The width of the plates 18 also bears such a relation to the thickness of the spacings 29 between the plates that flames or sparks are quenched by contact with the sides 45 of the plates before traverse of the spaces is completed.
- 45 The grid plates 18 are preferably constructed of material having non-corrosive and high heat radiating properties such, for example, as aluminum. The grids are inclined to the vertical as shown, whereby the outer face of each plate 18 has its bottom portion projecting beyond its top portion. The gases emerge from the grid in narrow laterally spaced zones corresponding to 50 the spaces 29. The described inclination of the

grid and the arrangement of the plates 18 in vertical rather than horizontal position, permits the escaping gases to ascend and burn freely with a minimum tendency to heat the grid.

The grid is protected from the elements by a 5 hood or shield 30 positioned adjacent to and spaced from its outer face in a manner to provide a combustion space 31 closed at the top and sides and open at the bottom for egress and ingress of air and vapors. The hood 30 is fastened 10 to the grid frame in any suitable manner by material fusible at relatively low temperatures, the fusible material preferably taking the form of pins or counter-sunk rivets 32. In the event of continued combustion in the space 31 at excessive 15 temperatures for a period tending to overheat the plates 18, the pins 32 will melt and permit the hood 30 to fall off before the plates 18 are heated to the melting point or to a temperature wherein the outflowing vapors will be ignited 20 by contact with the inner face of the grid. The melting temperature of aluminum grid plates is approximately 1200° F. The pins 32 are preferably constructed of an alloy of lead having a melting temperature of 300° F. or less.

If the oil has a perceptible salt or caustic material ingredient sufficient to corrode plates formed of aluminum or other high heat radiating materials, it is preferable that the grid plates be constructed of stainless steel or similar non-corrosive materials. Since stainless steel and like materials have low heat radiating properties, prolonged combustion at the emergent faces of grids comprising such materials may result in the inner ends of the grid plates being heated to 35 the ignition temperature of gases contacting therewith. In order that combustion resulting from such ignition at the inner surface of the grid may be limited to the immediate vicinity of the grid, I have provided an auxiliary or secondary flame arrester or baffle 33 positioned in closely spaced relation and preferably parallel to the inner face of the grid, as shown in Fig. 6. The baffle 33 may comprise a single screen of approximately forty mesh or two screens of approximately thirty mesh, spaced from one-fourth to one-eighth of an inch from the grid. Should the vapors be ignited by contact with an overheated grid, the combustion will be limited to the immediate vicinity of the grid since the volume of the gas in the space or pocket 34 is so small that ignition occurs without sufficient explosive pressure to reach or penetrate the screens. The suggested spacing of the baffle 33 from the grid prevents the screen from being heated to the 50 ignition point of gases and permits the free flow 55 of gases to the grid.

It also happens upon occasion that burning gases will be carried by high winds underneath the conduit and into contact with the valve housing 10. Baffle plates 35, fastened to and projecting below each grid, provide barriers preventing such burning gases from reaching the exterior of the valve housing.

Thus it will be seen that I have provided an 65 improved vapor conservation vent and flame arresting device for use with vent openings in oil or gas storage tanks or the like whereby combustion of vapors, disseminated by breathing of the tank, may occur either slowly or explosively 70 in proximity to the device without possibility of flames or sparks entering the device or reaching the vent opening, or that any portion of the device may become overheated.

Having thus described my invention, it is ob- 75

vious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

- 10 1. In a venting device, a horizontally extending conduit, a flame arrester mounted on one end of the conduit, said arrester comprising a plurality of vertically extending plates of high radiating material assembled side by side in slightly spaced relation to form a grid adapted to close the conduit to the passage of gases except through said spaces with the outer bounding ends of the plates inclined to and receding upwardly from the vertical towards the conduit, a plate member positioned outside of and in spaced relation to the grid to form a combustion chamber closed at the top and ends, said member being fastened to the conduit by means exposed to heat generated by combustion within said chamber, said means being fusible at combustion chamber temperatures below that sufficient to heat the opposite ends of the grid plates to a point wherein gases will be ignited by contact therewith, the fusing of said means resulting in the plate dropping away from the conduit.
- 15 2. A venting device comprising a casing providing a chamber, a horizontally extending conduit providing a port opening into the chamber, a pair of flame arresting grids respectively mounted in the opposite ends of the conduit, each grid comprising a plurality of vertically extending plates of high heat radiating material so arranged side by side in slightly spaced relation as to close the conduit to the passage of gases except through the spaces, the outer edges of the plates forming each grid being inclined to and receding upwardly from the vertical towards the conduit, a pair of plate members respectively positioned outside of and in spaced relation to the grids to form combustion chambers closed at the top and ends, said members being fastened to the conduit by means exposed to heat generated by combustion with the chambers bounded thereby, said means being fusible at combustion chamber temperatures below that sufficient to heat the opposite ends of the grid plates to the ignition point of gases contacting therewith, the fusing of said means resulting in the plates dropping away from the conduit.
- 20 3. The combination with a horizontally extending gas conduit, of a pair of flame arresting grids respectively mounted in the opposite ends of the conduit, each grid comprising a plurality of vertically extending plates arrested side by side in slightly spaced relation and comprising high heat radiating material, said grids closing the conduit to the passage of gases except through said spaces, the outer ends of the plates forming each grid being bounded by faces inclined to and receding upwardly from the vertical towards the conduit, a pair of plate members respectively mounted on the conduits outside of and in spaced relation to the grids to form combustion chambers closed at the top and ends, said members being fastened to the conduits by means exposed to heat generated by combustion within said chambers, said means being fusible at com-
- 25 bustion chamber temperatures below that sufficient to heat the inner ends of the grid plates to a point wherein gases will be ignited by contact therewith, the fusing of said means resulting in said plates dropping away from the conduit, a casing attached to the conduit and providing a chamber, said conduit providing inlet and outlet ports opening into the chamber, valve mechanism intermittently operable by pressure differentials in the casing chamber and the conduit to open and close the ports, and means for mounting the casing on a tank with the chamber connected with a vent opening in the tank.
- 30 4. The combination with a horizontally extending conduit, of a pair of flame arresting grids respectively mounted in the opposite ends of the conduit, each grid comprising a plurality of vertically extending plates arranged side by side in slightly spaced relation, said grids closing the conduit to the passage of gases except through said spaces, the outer ends of the plates forming each grid being bounded by faces inclined to and receding upwardly from the vertical towards the conduit, a pair of plate members respectively mounted on the conduit outside of and in spaced relation to the grids to form combustion chambers closed at the top and ends, said members being fastened to the conduit by means exposed to heat generated by combustion within said chambers, said means being fusible at combustion chamber temperatures below that sufficient to heat the inner ends of the plates to a point wherein gases will be ignited by contact therewith, the fusing of said means results in the plates dropping away from the conduit, a pair of auxiliary flame arresters each comprising a screen positioned in the conduit in close proximity to the grids, a casing attached to the conduit, said casing providing a chamber and said conduit providing inlet and outlet ports opening into the chamber, valve mechanism intermittently operable by pressure differentials in the casing chamber and conduit to open and close the ports, and means for mounting the casing on a tank with the chamber connected with a vent opening in the tank.
- 35 5. A flame arresting device for a gas venting and air inlet conduit of the kind described, said device comprising a closure member mounted on the open end of the conduit and providing a plurality of narrow restricted gas passages extending therethrough and respectively connecting the conduit within the atmosphere, the discharge face of said closure member being inclined in a direction to minimize contact therewith of the discharge gases, a hood member positioned in spaced relation to and forming a cover for said discharge face, said hood member having its upper and opposite lateral edges connected with the closure member to provide a combustion chamber between said members, said hood member being fastened in position by means exposed to heat generated by combustion of gases within said chamber, said means being fusible at a combustion chamber temperature below that sufficient to heat the inner portion of the closure member to a point such that gases will be ignited by contact therewith, the construction and position of said hood member being such that it will drop away from the closure member upon fusion of said fastening means.

RUDOLPH J. ANSCHICKS.
